UNITED STATES PATENT OFFICE.

CHARLES E. JOHNSON, OF MUSKEGON, MICHIGAN.

MECHANISM FOR MACHINING OUT-OF-ROUND PISTON-RING CASTINGS.

Application filed September 7, 1920. Serial No. 408,507.

To all whom it may concern:

Be it known that I, CHARLES E. JOHNSON, a citizen of the United States of America, residing at Muskegon, in the county of Muskegon and State of Michigan, have invented certain new and useful Improvements in Mechanism for Machining Out-of-Round Piston-Ring Castings; and I do hereby declare the following to be a full, clear, and exact description of the invention, such as will enable others skilled in the art to which it appertains to make and use the same.

This invention relates to a novel mechanism and apparatus for machining piston ring castings.

In the manufacture of piston rings it is the best practice to make an individual ring casting for each piston ring to be produced, the same being cast in what is known as out-of-round and not in true circular form, such that on removal of a gap piece at one side of the ring casting and bringing the ends at the parting thus made together a ring of true circular form is made.

Heretofore it has been usual to finish each end of the ring casting and rough grind its outer curved surface after which the gap piece was removed, the casting being afterward compressed into true circular form and the outer surface of the ring casting then finished, first by taking a roughing cut followed by a finishing cut which completed the ring. It is, of course, necessary that the casting be in practically true circular form when the finishing at the outer curved surface is done in order to make rings of uniform thickness.

The present invention is directed to a mechanism by means of which the ring may be acted upon and partially finished at its outer curved surface prior to the removal of the gap piece at one side of the ring; particularly the rough cut at the outer curved surface of the ring casting may be done before the ring casting is parted at one side. From this an elimination of the necessity of testing each casting for thickness after it has been rough ground follows. My invention is directed to a relatively simple mechanism by means of which the individual ring casting may be distorted from its normal out-of-round form, held to a substantially true circular form, rotated while so held and machined at its outer curved surfaces while thus held and

rotated. The invention comprises many novel features of construction and details of mechanism for accomplishing this end as will appear fully and in detail from the following description taken in connection with the accompanying drawings, in which;

Fig. 1 is a front elevation of a lathe equipped with my invention.

Fig. 2 is a plan view of the tail stock portion of the lathe.

Fig. 3 is a central vertical section taken through a head which is connected to the head stock spindle of the lathe.

Fig. 4 is a similar section taken through the head used with and connected to the tail stock spindle.

Fig. 5 is an end elevation of the head shown in Fig. 3, and

Fig. 6 is a similar end elevation of the head shown in Fig. 5.

Like reference characters refer to like parts in the different views of the drawing.

The lathe has the usual bed 1, head and tail stocks 2 and 3 and the common and well known tool support indicated at 4. The tail stock spindle 5 is of the quick action type being slidably mounted through the tail stock and operated by a link 6 pivotally connected at one end thereto, its opposite end having connection to an operating handle 7 which is pivotally mounted on and above the tail stock. By this construction the spindle 5 may be moved quickly back and forth.

On the head stock spindle 8 of the lathe a head is adapted to be detachably connected, the same consisting of a cylinder 9 interiorly bored and threaded as indicated at 10 so that it may be screwed on the end of the head stock spindle. The head 9 is provided with a central reduced extension 11 over which a collar 12 is placed, the same being connected with the head 9 so as to turn therewith by a pin 13 attached to the head and entering a recess 14 in the collar as shown in Fig. 3. Collar 12 adjacent its outer side is cut to provide an annular conical surface 15 entirely around the collar. This collar 12 is formed of tool steel, preferably, and is tempered so that the conical surface 15 is very hard and capable of sustaining severe usage. The collar is formed with an annular recess 16 at its outer side whereby a securing nut 17 may be threaded onto the end of the projection 11 and lie flush with the outer side of the

5 collar, any suitable spanner wrench being used for operating the nut, the nut being formed with diametrically opposed recesses 18 for the attachment of the wrench. In 10 the outer side of the collar 12 between the conical surface 15 and the recess 16 a continuous series of openings 19 are bored as shown.

10 The inner end of the tail stock spindle 5^a is formed with a flange 20 having a diameter greater than that of the tail stock spindle, in front of which extends a cylindrical projection 21, the diameter of which is between that of the flange 20 and the spindle 5^a. 15 Over projection 21 two disks 22 and 23 are placed between which a successive series of balls 24 are located, the same traveling in suitable races made in the adjacent faces of the disks. A member 25 is likewise placed 20 over the end of the projection 21 it being formed with an integral sleeve portion 26 to enclose disks 23 and 24 and the balls between the same and protect the bearings against the entrance of dust or other undesirable foreign substance. The member 25 is formed with a recess in its outer portion which leaves an annular lip 27 around the end of the extension 21 and the parts are connected together by a head 28 which is 25 detachably connected to and lies against the end of the projections 21 and one lip 27, any suitable means of connection, such as a screw indicated in dotted lines in Fig. 4, being used. This head 28 is located in 30 the recess made in the member 25.

35 A hardened disk or plate 29 having the same diameter as the collar 12 is placed against the member 25 and secured thereto by a plurality of screws 30. A pin 31 of a 40 size adapted to freely enter any of the openings 19 projects in front of the face of disk 29.

45 In operation an out-of-round ring casting of a size to pass over and against the conical surface 15 is placed against said surface, handle 7 then grasped and the head on the tail stock spindle moved to the opposite side of the ring casting and pressed firmly against the same. When this is done 50 the ring casting is sprung from its out-of-round form and shaped to fit the conical surface 15 thereby distorting the casting to a circular form. The pin 31 enters one of the 55 openings 19 and it is apparent that with the rotation of the head 9 and attached parts the plate 29, member 25 and disk 23 turn freely about the cylindrical projection 21, the disk 23 riding freely on the balls 24. The ring held between the heads also turns 60 with them. The outer face of the plate 29 is held at all times in the same plane perpendicular to the axis of the head stock spindle. This insures that the pressure exerted on a ring casting cast normally out-of-round will cause it, when brought against 65

70 the conical surface 15 of collar 12, to assume a circular form, whereupon a tool carried by the tool holder 4 of the lathe may be fed lengthwise of the ring casting and a cut taken therefrom. This cut, the first roughing cut taken from the casting removes the outer scale from the casting and also any irregularities and extra thicknesses of metal, leaving the ring casting in shape such that 75 after the parting has been made in a side thereof only one more operation is needed, that being a finishing cut of a very small amount. As soon as the tool has finished a cut on the ring casting the handle 7 is grasped and the spindle 5 removed in 80 the opposite direction, this releasing the ring and permitting it to assume its normal out-of-round form. The ring drops from the end of the collar 12 into any suitable receptacle placed to receive it. 85

90 This construction of mechanism for machining out-of-round ring castings is relatively simple and with it the castings may be machined very rapidly. In fact the feed of the cutting tool may be automatic and all that the operator has to do is to press the rings against the conical surface 15 and operate the handle 7 for the holding and releasing of the castings. The advantages 95 which arise and the steps saved in finishing piston rings are fully outlined in my application on the method of machining piston ring castings, the method not being limited to any one particular construction of machine and being the subject matter of a co-pending application. 100

105 The appended claims define the invention and I consider myself entitled to all modifications which fall within their scope.

I claim:

110 1. A mechanism of the character described, a spindle mounted for rotation, a head secured to said spindle and provided with an annular conical surface at its free end against which one side of an out-of-round piston ring casting is adapted to be placed, a second spindle in alignment with the first spindle, a second head mounted on said second spindle including a part adapted to turn about the longitudinal axis of the 115 spindle, said second head having a face disposed in a plane perpendicular to the axis of the spindle, means for moving said second spindle and attached head so as to bring said face of the head against the opposite side of the ring casting, and means for connecting the heads together when said second head is moved toward the first head, substantially as described. 120

125 2. In combination, a rotatably mounted spindle, a head thereon formed at its free end with an annular conical surface against which one side of an out-of-round piston ring casting is adapted to be placed, a second head mounted a short distance from 130

the first head, means for moving one of said heads toward the other head to clamp the ring casting between the heads and force the casting against said conical surface whereby 5 said ring casting is sprung to circular form and firmly held between the heads to rotate therewith, substantially as described.

3. In a mechanism of the character described, a rotatably mounted spindle, a head 10 secured thereon and provided with an annular conical surface at its free end against which one side of an out-of-round piston ring casting may be placed, a second spindle slidably mounted in alinement with the 15 first spindle, a second head rotatably mounted on the inner end of said second spindle and formed with a face adapted to come against the opposite side of the piston ring casting and thereby force the ring casting 20 against said conical surface and distort it to circular form, and means for connecting the heads together when the second spindle is moved to bring its head toward the first head to clamp said ring casting between 25 them, substantially as described.

4. In combination, a rotatably mounted spindle, a head thereon provided at its free end with an annular conical surface and with a plurality of openings located in a

circle in the free end of the head, a second 30 spindle slidably mounted in alinement with the first spindle, a second head rotatably mounted at the inner end of the second spindle, said second head having a face lying in a plane perpendicular to the axis of 35 said spindles, and a pin projecting from said second head and adapted to enter any one of said openings in the first head to connect the heads together for rotation, substantially as and for the purposes described. 40

5. In combination, a lathe provided with head and tail stocks, a spindle rotatably mounted on the head stock, a spindle slidably mounted through the tail stock in alinement with the head stock spindle, 45 a head formed with an annular conical surface at its free end secured to the head stock spindle, a second head rotatably mounted on the inner end of the tail stock spindle, said second head including a face plate having 50 an outer face lying in a plane perpendicular to the axis of the spindles, and means for instantaneously connecting the heads together when the tail stock spindle is moved to bring its head to the head on the head 55 stock spindle, substantially as described.

In testimony whereof I affix my signature.
CHARLES E. JOHNSON.
